PHOTOGRAPHIC LAYER AND PROCESS OF
PRODUCING SAMEWillem Pieter Maria Josef Robijns, Mortsel,
Belgium, assignor to Gevaert Photo-Producten,
N. V., Oude-God, Antwerp, BelgiumApplication April 27, 1937, Serial No. 139,185
In Austria May 2, 1936

6 Claims. (Cl. 95—7)

My invention relates to means for producing photographic images and more especially to the production of images giving the impression of a great plasticity.

5 It is an object of my invention to provide means for producing images, in which the fore- and background lie in one plane, but which convey to the onlooker the impression of the three-dimensional object reproduced by the image. As 10 a rule this effect is styled "stereoscopic" or "plastic".

My invention comprises both the photographic article such as a light-sensitive layer arranged on a suitable carrier, with the aid of which such 15 images can be produced, and the process of making this article.

As is well known to those skilled in the art, light-sensitive papers of velvet-like appearance, which display a certain plastic effect, are obtained by fixing on the carrier (the paper) vegetable or animal fibres by means of a suitable binder and arranging the light-sensitive layer 20 on this carrier, after the binder has dried down completely.

25 I obtain light-sensitive layers imparting to the images produced with their aid a great plasticity by incorporating in the emulsion forming the light-sensitive layer fine grains capable of agglomerating in the layer to form comparatively 30 coarse aggregates, or I may introduce both fine and coarse grains. I have found granules of the order of those passing through a sieve with about 20 meshes per linear centimetre to be most suitable for my purpose.

35 The agglomerated granules impart to the light-sensitive layer a surface which reflects the light rays repeatedly in succession, whereby a plastic effect is produced. The image produced in a 40 layer according to this invention is not confined to the two dimensions of a plane, but the third dimension is utilized also in the formation of the image.

The granular substance to be incorporated in the light-sensitive layer may be of an organic 45 or inorganic nature. Since in the production of the light-sensitive layer large quantities of granules are used without paying regard to their specific gravity, which may be high, the granules should possess a low covering power. I therefore prefer organic substances such as artificial 50 resin, or inorganic products such as silicates, for instance ground glass. Preferably the covering power of the granular matter should be lower than that of barium sulfate.

55 A light-sensitive layer according to my inven-

tion may consist for instance of a photographic silver halide emulsion, in which are distributed granules resulting from the agglomeration of fine or fine and coarser particles of the nature and dimensions here above described, this layer being 5 arranged on a suitable carrier, for instance on paper.

In the drawing affixed to this specification and forming part thereof an article embodying my invention is illustrated in a purely diagrammatical manner and on a greatly exaggerated scale 10 by way of example in cross section.

1 is the carrier, 2 is the photographic layer containing silver halide, 3 are comparatively large sized granules embedded in this layer which are combined by agglomeration with small sized granules 4 and are so arranged in the photographic layer as to render its surface rough and uneven.

If a photographic image is produced on this 20 layer by exposure to light in the camera or under a negative and subsequent development, this image will impart to the onlooker the impression of having before him not a plane image, but the article itself which is reproduced by the image. 25

Various changes may be made in the details disclosed in the foregoing specification without departing from the invention or sacrificing the advantages thereof.

I claim:

1. As a new article of manufacture, a light-sensitive layer comprising a photographic silver halide emulsion and a plurality of agglomerates of granules of different sizes distributed in this emulsion and rendering the surface of the layer 35 uneven, said agglomerates being of the order of granules passing through a sieve of 20 meshes per linear centimetre.

2. As a new article of manufacture, a light-sensitive layer comprising a photographic silver 40 halide emulsion and a plurality of granules distributed in this emulsion and rendering the surface of the layer uneven, said granules being of the order of granules passing through a sieve of 20 meshes per linear centimetre, some of the 45 granules being agglomerates of coarse and fine grains.

3. As a new article of manufacture, a light-sensitive layer comprising a photographic silver halide emulsion and a plurality of agglomerates 50 of organic matter distributed in this emulsion and rendering the surface of the layer uneven, said agglomerates being of the order of granules passing through a sieve of 20 meshes per linear centimetre.

4. As a new article of manufacture, a light-sensitive layer comprising a photographic silver halide emulsion and a plurality of agglomerates of inorganic matter distributed in this emulsion and rendering the surface of the layer uneven, said agglomerates being of the order of granules passing through a sieve of 20 meshes per linear centimetre.
5. The method of producing a photographic article which comprises distributing in a photographic emulsion, a plurality of granules which are agglomerates of the order of granules passing through a sieve of 20 meshes per linear centi-

metre in such manner as to produce a light-sensitive layer having an uneven surface and depositing the emulsion containing these agglomerates on a carrier.

6. As an article of manufacture, a light-sensitive layer comprising a photographic silver halide emulsion and a plurality of granules of at least two widely different sizes forming agglomerates of the order of granules passing through a sieve of 20 meshes per linear centimetre which are so distributed in this emulsion as to render the surface of the layer uneven.

WILLEM PIETER MARIA JOSEF ROBLJNS.
